CLAIM

The ornamental design for a combined spoon/knife and spork utensil assembly, as shown and described.

DESCRIPTION

FIG. 1 is a top perspective view of a combined spoon/knife and spork utensil assembly showing the claimed design.

FIG. 2 is a front side view thereof.

FIG. 3 is a back side view thereof.

FIG. 4 is a right side view thereof.

FIG. 5 is a left side view thereof.

FIG. 6 is a top plan view thereof.

FIG. 7 is a bottom plan view thereof.

FIG. 8 is a bottom perspective view thereof.

FIG. 9 is a top exploded view thereof; and,

FIG. 10 is a bottom exploded view thereof.

(Continued)

FIG. 9 and FIG. 10 are provided for context only and are not claimed. As such, FIG. 9 and FIG. 10 are depicted entirely in broken lines and form no part of the claimed design.

1 Claim, 7 Drawing Sheets
